UNITED STATES PATENT OFFICE

2,256,620

ADJUSTABLE SHORE

Charles M. Markham, Birmingham, Ala.

Application July 30, 1940, Serial No. 348,405

4 Claims. (Cl. 248—354)

My invention relates to adjustable shores adapted for use in mining, building, etc., and has for an object the provision of a shore which is inexpensive in construction, simple and reliable in operation, and which will not readily get out of order.

My invention further contemplates the provision of a shore having a base portion and a vertically adjustable member in the form of a squared timber which is mounted for telescopic movement in the base member. A head portion is formed on the upper end of the base portion to receive a dog and a wedge which serve to lock the adjustable member against vertical movement with respect to its base member. When the shore is to be removed from its supporting position the wedge is knocked out of engagement with the dog to permit the dog to disengage the adjustable member. When the shore is employed as a temporary support for a mine roof, it is advisable to be at a distant point when the shore is removed and it is, therefore, an object of my invention to provide a wedge operating block which may be actuated at a remote point through a rope or cable to disengage the dog from the adjustable member. The shore may then be pulled out of the danger zone by means of the rope or cable.

My invention further contemplates the provision of an adjustable cap board to be mounted on the upper end of the adjustable member. A pivotal mounting is provided for the cap board in order that the cap board will move into alignment with sloping or uneven roofs. A wedge is employed for adjusting the cap board vertically with respect to the adjustable member.

My invention embodies other novel features, details of construction and arrangement of parts which are hereinafter set forth in the specification and claims and illustrated in the accompanying drawing, forming part thereof, wherein:

Fig. 1 is a front elevational view showing my improved adjustable shore; and

Fig. 2 is a sectional view taken along the line II—II of Fig. 1.

Referring now to the drawing for a better understanding of my invention, I show an adjustable shore comprising a base member 6 having an adjustable member 7 mounted for telescopic movement therein. The base member comprises a pair of channels 8 and 9 having their flanges facing inwardly to define an opening adapted to receive the adjustable member 7 for vertical movement therein. The channels 8

and 9 are joined to each other by means of straps 10 which are preferably formed U-shaped and having their ends welded to the web portion of the channels. A plate 11 is welded to the lower ends of the channels to provide a foot for the base member. The channel members 8 and 9 are preferably formed of sheet steel of relatively light gauge and provided with axially extending beads 12 which add considerably to the load carrying capacity of these members and also contribute to the ornamental appearance.

A head portion 14 is provided on the upper end of the base member 6 and embodies a housing 16 which extends outwardly and downwardly from the side walls 17 and 18 and the back wall 19 which enclose, and are welded to, the upper ends of the channels 8 and 9. Apertures 21 and 22 are formed in the housing 16 to receive a wedge member 23. Each aperture is formed to provide inwardly facing ears 24 which serve as guides for the wedge member by engaging the side flange 25 thereof. A block of hardened steel 26 is mounted in the housing to serve as a friction bearing for the wedge. A rivet 27 is provided in the lower end of the wedge for engagement with the ears 24 to prevent accidental displacement of the wedge from the housing. Beads 28 are formed in the back wall 19 of the housing.

30 A dog 30 is mounted within the housing 16 and is formed with a toothed front surface 31 for engagement with the adjustable member 7. The other end of the dog is formed with a rounded bearing surface 32 for engagement by 35 the wedge 23 and with side flanges 33 having inwardly disposed lugs 34 for engagement behind the side flange 25 of the wedge. A spring 35 is secured in the housing below the forward end of the dog to yieldably resist a downward 40 movement of the forward end of the dog.

A dog release hammer 36 formed of metal is suspended below the housing 16 on a rope or cable 37 which has its ends fastened in openings 38 by lock washers 39. A guide member 40 is welded to the bottom of the housing and provided with eyes 41 to receive and guide the rope 37. A clip 42 is fastened to the rope 37 at its center and to a rope or cable 43 which may be of any suitable length. A tongue 44 is 45 formed on the hammer to engage in the groove 50 formed between the beads 12 which serve as guides for the hammer when it is moved vertically.

The lips 46 and 47 formed on the side walls 17 and 18 of the head portion 14 for engagement by

a lifting lever (not shown) of the type shown in a patent issued to me on March 1, 1932, Number 1,847,660, form no part of the present invention.

The adjustable member 7 is formed of wood and is preferably square in cross section. A cap member 51 is formed having four side walls 52 and a partition plate 53 welded thereto to fit over the top end of the member 7 and to be secured thereto by means of a bolt 54. Apertures 55 and 56 are formed in oppositely disposed side walls to receive a wedge member 57, and the apertures are formed to provide inwardly disposed ears 58 which engage the inner side of the wedge flange 59 to serve as guides for the wedge. A rivet 60 is mounted on the small end of the wedge to prevent removal of the wedge from its apertures. A bracket 61 is provided to receive a cap board 62 thereon and comprises a top plate 63, a bearing plate 64, and guide plates 65 which are all welded together. A T-shaped slot 66 is formed in the bearing plate 64 to receive the flange 59 of the wedge.

In the operation of the shore heretofore described, the adjustable member 7 is moved to its desired position and then locked by driving the wedge 23 downwardly to move the dog into engagement with the adjustable member. When the cap board is used, the wedge 57 is then driven inwardly to move the bracket 61 vertically against the roof or object being supported. In removing the shore from its supporting position, the operator pulls on the rope 43 to drive the hammer 36 against the small end of the wedge 23 to raise same, thereby disengaging the dog 30 from the member 7. The rope 43 is then employed to draw the shore out from under an unsupported and unsafe mine roof.

I claim:

1. In an adjustable shore, a base member, an adjustable member mounted for vertical movement in said base member, a dog housing provided on the base member, a dog positioned within said housing for engagement with said adjustable member, a wedge for moving said dog into and out of engagement with the adjustable member, a hammer for driving the wedge into position to disengage the dog from the adjustable member, and means for actuating said hammer.

2. In an adjustable shore, a base member, an adjustable member mounted for vertical movement in said base member, a dog housing provided on the base member, a dog positioned within said housing for engagement with said adjustable member, wedge means engaging the dog for moving same into and out of engagement with the adjustable member, and spring means for yieldably resisting a downward movement of the forward end of the dog.

3. In an adjustable shore, a base member, an adjustable member mounted for vertical movement in said base member, a dog housing provided on the base member, a dog positioned within said housing for engagement with said adjustable member, wedge means for moving the dog into and out of engagement with the adjustable member, a hammer mounted on the base member for actuating the wedge means to move the dog out of engagement with the adjustable member, and a rope for actuating said hammer.

4. A device according to claim 3 in which, means is provided for guiding the vertical movement of the hammer.

CHARLES M. MARKHAM.
